UNITED STATES PATENT OFFICE

150,222

DESIGN FOR A TIRE CHAIN TOOL

Everett L. Gile, Billerica, Mass.

Application January 15, 1947, Serial No. 136,151

Term of patent 14 years

(Cl. D54—13)

To all whom it may concern:

Be it known that I, Everett L. Gile, a citizen of the United States, residing at Billerica, in the county of Middlesex and State of Massachusetts, have invented a new, original, and ornamental Design for a Tire Chain Tool, of which the following is a specification, reference being had to the accompanying drawing, forming a part thereof.

Fig. 1 is a side elevational view of a tire chain tool showing my new design;

Fig. 2 is an edge view; and

Fig. 3 is a view opposite to that shown in Fig. 1.

I claim:

The ornamental design for a tire chain tool, substantially as shown.

EVERETT L. GILE.
